UNITED STATES PATENT OFFICE.

DANIEL B. LUTEN, OF INDIANAPOLIS, INDIANA.

BEAM.

1,078,365.

Specification of Letters Patent. Patented Nov. 11, 1913.

Application filed November 28, 1910. Serial No. 594,482.

To all whom it may concern:

Be it known that I, DANIEL B. LUTEN, a citizen of the United States, residing at Indianapolis, in the county of Marion and 5 State of Indiana, have invented a new and useful Improvement in Beams, of which the following is a specification.

My invention relates to improvements in reinforcement for concrete beams, whereby 10 the beam is not only strengthened without increased cost, but is actually cheapened in cost by reason of greater facility of construction.

The invention is illustrated in the accompanying drawings in which the same reference characters designate like parts throughout the several views and in which;—

Figure 1 is a longitudinal section through a beam and its supports, and Fig. 2 is a detail view of the reinforcing members.

A concrete beam has regions of compression throughout most of its loaded surface and corresponding regions of tension opposite, usually a maximum at the middle of 25 the span or opposite the point of application of a concentrated load. The beam also has regions of tension between upper and lower surfaces at about one quarter of the span tending to produce diagonal cracks. If the 30 beam has fixed ends there will also result regions of tension on the loaded side over the supports. All of these tension regions are effectively reinforced by continuous tension members such as metal rods, following 35 the unloaded face closely throughout the middle of the span, and then crossing in a diagonal direction upward to follow the loaded face closely over the supports. But since the diagonal tension is distributed 40 throughout a considerable area lengthwise of the beam, it is desirable to use two or more tension members so displaced with respect to one another that the diagonal reinforcement will be distributed over a consider- 45 able length of the beam, say one fourth the span. Thus in Fig. 1, the beam 1 resting upon its supports 2, is reinforced by two rods 3 and 4 following closely the surface 5 opposite the load A and then crossing dia- 50 ginally through the region of diagonal tension 6 at distributed points 3 and 4 to follow the loaded surface closely over the supports at 7. The reinforcing bars shown in Fig. 2 are identical but longitudinally reversed, the 55 end 8 of each bar being identical in length, and similarly with respect to the other end

7 and the diagonals 3 and 4. The intermediate portion 9 is the same in both. If now, these two identical but reversed bars be embedded in the beam side by side, the reinforced beam of Fig. 1 results. In the case of a beam with free ends instead of fixed, where no tension exists over the supports, the ends 7 and 8 of both rods may be omitted or replaced by short anchorage portions 65 and the same relations will still exist.

A decided advantage results in the fabrication of the reinforcement for a beam as described in that but a single form of bar need be bent to provide reinforcement 70 throughout all of the essential tension regions. Only one lay-out of the form of bar need be made on the drawings. Simplicity of reinforcement results and is of the greatest advantage because of the unskilled labor 75 usually employed in the fabrication and placing of such members, and because of loss otherwise occasioned by failure of complicated elements to arrive promptly. This new arrangement of reinforcement moreover 80 produces a beam of increased strength, for as the load assumes the position shown at B the tensile stresses in their greatest intensities move to the right with the load. But the bar 4 is properly placed to resist them. 85 Whereas for the load moving to the other end of the beam, the bar 3 is advantageously located. And at the same time a maximum of tension reinforcement results near the middle of the span for heavy uniform load- 90 ing throughout. The invention may of course be amplified to include any number of reinforcing members.

I claim;

1. A beam reinforced with embedded tension members, each of said members having a middle portion adjacent the unloaded face of the beam, and a diagonal portion crossing the beam at each end of the middle portion with end portions of unequal length 95 following the loaded face of the beam closely near each end, said reinforcing members being similarly formed but reversely embedded in pairs so that the diagonals cross the beam at different distances from the middle of the span.

2. A beam reinforced with similar embedded tension members, each of said members having a middle portion adjacent the unloaded face of the beam, and a diagonal 100 portion crossing the beam at each end of the middle portion, the two ends of each mem-

ber being at different distances from the middle portion and some of said reinforcing members being reversed with respect to others of said members, so that the diagonals cross the beam at different distances from the middle of the span.

3. A reinforcing for concrete beams, comprising a plurality of substantially identical tension members, each non-symmetrical 10 on opposite sides of its center, said members being turned end for end with respect to one another, and arranged to cross the beam diagonally near each end and to follow one face of the beam closely between.
- 15 4. A beam reinforced with a plurality of substantially identical tension members, each of such members having a middle portion adjacent the unloaded face of the beam, diagonal portions crossing the beam at the

ends of the middle portion, and an end portion extending from each diagonal portion and following the loaded face of the beam closely; one end portion of each member being longer than the other, and the members being placed so that their ends are all 25 in substantial alinement transversely of the members and some of the members are turned end-for-end with respect to the others.

In witness whereof, I have hereunto set 30 my hand and seal at Indianapolis, Indiana, this 16th day of November, A. D. one thousand nine hundred and ten.

DANIEL B. LUTEN. [L. s.]
